(57) **CLAIM**

The ornamental design for a scooter as shown and described.

DESCRIPTION

FIG. 1 shows a perspective schematic drawing of the scooter in accordance with the present invention;
FIG. 2 shows a right-side-view schematic drawing of the scooter of FIG. 1;

FIG. 3 shows a left-side-view schematic drawing of the scooter of FIG. 1;

FIG. 4 shows a front-view schematic drawing of the scooter of FIG. 1;

FIG. 5 shows a rear-view schematic drawing of the scooter of FIG. 1;

FIG. 6 shows a top-view schematic drawing of the scooter of FIG. 1; and,

FIG. 7 shows a bottom-view schematic drawing of the scooter of FIG. 1.

The broken lines showing an attached accessory in FIG. 3 are for the purpose of illustrating portions of the scooter that form no part of the claimed design. The shade lines shown in the drawing represent the three-dimensional contour of the design, and are not intended to indicate surface decoration.
